[57] CLAIM

The ornamental design for a "toy train caboose", as shown
and described.

DESCRIPTION

FIG. 1 is a top, front and right side perspective view of a toy
train caboose according to my design, wherein a front,
right-side gate shown in FIGS. 2, 4, and 6, has been removed
to show certain ornamental figures behind the gate;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.
